HIRAM W. HAYDEN, OF WATERBURY, CONNECTICUT, ASSIGNOR TO HOLMES,
BOOTH & HAYDENS, OF SAME PLACE.

Design No. 4,829, dated April 18, 1871.

DESIGN FOR A LAMP-BURNER.

The Schedule referred to in these Letters Patent and making part of the same.

To all whom it may concern:

Be it known that I, HIRAM W. HAYDEN, of Waterbury, in the county of New Haven and State of Connecticut, have invented or produced a new and original Design for the Shape and Configuration of a Lamp-burner.

The same is shown in the annexed drawing, wherein—

Figure 1 is an elevation of said burner, and
Figure 2 is an inverted plan of the same.

The air-distributer *a* is made of a flaring form, with a compound or ogee configuration, and above this is a projecting bead, *b*, forming the outer edge of the chimney-rest, and above this is the spring chimney-

holder *c*, made with open work of configuration, shown in fig. 1.

The cone *d* is made as a tapering outline, curved as represented.

I claim as my invention—

The design of the ornamental shape and configuration of the air-distributer *a*, bead *b*, and chimney-holder *c*, as set forth and shown.

Signed by me this 9th day of March, A. D. 1871.
H. W. HAYDEN.
